TELEPHONE ENCLOSURE

Donald Michael Genaro, Haworth, N.J., John Niel Mc-
Garvey, Drexel Hill, Pa., and Gordon Elliot Sylvester,
Jamaica, N.Y., assignors to Bell Telephone Labora-
tories, Incorporated, Murray Hill, N.J.

Filed Apr. 13, 1973, Ser. No. 351,082

Term of patent 14 years

Int. Cl. D14—03
U.S. Cl. D26—14 A

FIG. 1

FIG. 2

FIG. 3

FIG. 4

FIG. 5

FIG. 6

FIG. 7

FIG. 8

FIG. 1 is a perspective view showing the top, front and one side of our new design for a telephone enclosure;

FIG. 2 is a top plan view of the telephone enclosure;

FIG. 3 is a front view of the telephone enclosure;

FIG. 4 is a side view of the telephone enclosure; the opposite side being essentially a mirror image of the side shown;

FIG. 5 is a perspective view of the telephone enclosure with the lid portion open;

FIG. 6 is a top plan view of the telephone enclosure with the lid portion open;

FIG. 7 is a front view of the telephone enclosure with the lid portion open; and

FIG. 8 is a side view of the telephone enclosure with the lid portion open, the opposite side being essentially a mirror image of the side shown.

We claim:

The ornamental design for a telephone enclosure, substantially as shown and described.
